Attorney's

UNITED STATES PATENT OFFICE.

FRANK M. BASHELIER, OF JENKINTOWN, PENNSYLVANIA, ASSIGNOR TO KEYSTONE TYPE FOUNDRY, OF PHILADELPHIA, PENNSYLVANIA, A CORPORATION OF PENNSYLVANIA.

PRINTER'S CABINET.

1,121,453.

Specification of Letters Patent. Patented Dec. 15, 1914.

Application filed August 6, 1913. Serial No. 783,426.

To all whom it may concern:

Be it known that I, FRANK M. BASHELIER, a citizen of the United States, residing at Jenkintown, Montgomery county, and State 5 of Pennsylvania, have invented and discovered certain new and useful Improvements in Printer's Cabinets, of which the following is a specification.

My said invention consists in certain improvements in the details of construction and arrangement of parts of a printer's cabinet, of that general character forming the subject matter of my Patent 1,057,372, but designed especially for printers' use in 10 newspaper offices, whereby such a cabinet is provided wherein the type, lead, slugs, and other materials used, are held and stored in a most convenient arrangement for use and also a convenient "make-up" table 15 is provided having a flat working surface suitable for newspaper make-up work, thereby combining both the composition and "make-up" conveniences in a single cabinet, all as will be hereinafter more fully described and claimed.

Referring to the accompanying drawings, which are made a part hereof and on which similar reference characters indicate similar parts, Figure 1 is a view showing one 20 side of my improved cabinet in elevation, Fig. 2 a similar view showing the other side, and Fig. 3 a similar view showing an end elevation.

The main frame work, or casing 10 of the 25 cabinet, is preferably of steel and of any appropriate construction. Its side shown in Fig. 1 is filled with type cases and its top above said type cases is provided with a sloping work-bank 11 adapted for well 30 known use. The sloping work-bank 11 preferably extends from the flush side of the frame at its lower edge back to a point beyond the center line of the cabinet or nearly to above the opposite side of said cabinet, 35 and elevated above the flat "make-up" table of the opposite side. Said flat "make-up" 40 table 12 projects for a considerable distance beyond the opposite edge of said casing 10 and also extends backward beneath the rear 45 edge of the sloping work-bank 11, preferably to beyond the center line, a sufficient 50 space being provided between the under side of the rear edge of the flat "make-up" table

to accommodate the forms and afford room to handle and take care of the matter contained therein. 55

Beneath the overhanging edge of the flat "make-up" table 12 are provided drawers 13 and an open pocket 14 for convenience in storing material to be used. Above the 60 make-up table 12 and supported from the rear edge of the sloping work-bank 11, is mounted in an inclined position a type, slug and lead containing case 15 in convenient 65 position for use.

Beneath the drawers 13 on the face of the casing 10 is mounted a shelf 16 in an inclined position, as in my patent before referred to.

In use the cabinets may be arranged in 70 the composing room as explained in my above mentioned patent, or in any convenient manner. By reason of the flat "make-up" table 12, the cabinet is especially adapted for newspaper offices and work as a large 75 "make-up" surface is immediately and conveniently available in connection with the cabinet containing all the type or material for making up the forms.

Having thus fully described my said invention, what I claim as new and desire to secure by Letters Patent, is:

1. A printer's cabinet comprising a casing, an inclined work-bank on the top of said casing extending from one edge in an 85 upwardly inclined direction substantially across the top of said casing, and a flat "make-up" table on the opposite side of said casing extending for a distance beneath the rear edge of said inclined work-bank 90 and overhanging the outer edge of said casing, substantially as set forth.

2. A printer's cabinet comprising a casing, an inclined work-bank extending longitudinally on the top of said casing and 95 from one edge rearwardly to beyond the center line of said casing, a flat "make-up" table on the opposite side of the top of said casing extending for a distance beneath the rear edge of said work-bank and extending 100 outwardly for a considerable distance beyond the casing, substantially as set forth.

3. A printer's cabinet comprising a casing with a top having a work-bank inclined 105 downwardly from an intermediate point toward one side of the cabinet, and a flat

"make-up" table extending from an intermediate point toward the other side of the cabinet, the inner edge of the flat "make-up" table extending beneath and at a distance below the inner edge of said inclined work-bank, substantially as set forth.

In witness whereof, I have hereunto set

my hand and seal at Philadelphia, Pennsylvania this 18th day of July, A. D. nineteen hundred and thirteen.

FRANK M. BASHELIER. [L. s.]
